SHIP AND LOADING GEAR

Thomas D. Bowes, Cynwyd, Pa.

Application February 8, 1945, Serial No. 576,881

6 Claims. (Cl. 214—15)

1

My invention is designed to provide improved means for loading and unloading a ship expeditiously and economically.

In accordance with my invention, one or more deck runways for a crane-carriage or crane-carriages are provided extending longitudinally a major portion of the length of the cargo holds and preferably along both gunwales of the ship and outboard from the hatchway coamings.

Each runway is provided with a track composed of rails forming a rack and closed races on opposite sides of the rack. These rails coact with rollers or wheels on a carriage to longitudinally translate and prevent the tilting of the carriage.

The carriage non-tiltably supports a hollow, power slewed rotor or rotatable housing upon which is mounted loading mechanism, such as a crane, having a fulcrumed boom provided with lifting and topping cables. These cables may be wound on and unwound from suitable drums driven from motors housed within the rotor and controlled from a cab mounted on the rotor, from which the translating and slewing motors may also be controlled.

By my improvements there is provided a relatively light, balanced loading gear having a low center of gravity, requiring no counterbalancing weights or shrouds, and interposing no obstruction to visibility or to passing under bridges when stowed and a minimum obstruction to visibility when in operation.

My improved gear permits great flexibility of operation so that the ship may be loaded from a dock or lighter or both, or loaded from one while unloading onto the other and all holds may be prepared for battening down the hatch covers at about the same time. Furthermore the several cranes may be used individually or cumulatively according to the weight of the load to be lifted, and may even be employed for assisting in the unloading of a different ship from that on which they are mounted.

The characteristic features and advantages of my improvements will further appear from the following description and the accompanying drawings in illustration thereof:

In the drawings, Fig. 1 is a top plan view of a ship embodying my invention; Fig. 2 is a side elevation of the ship shown in Fig. 1; Fig. 3 is a somewhat diagrammatic transverse sectional view illustrating the operation of my improved loading mechanism for the loading of the ship shown in Figs. 1 and 2; Fig. 4 is an enlarged top plan view of one of the loading mechanisms and of a portion of the deck and coaming, with parts broken away; Fig. 5 is a side elevation of the loading mechanism and a part of the track shown in Fig. 4; Fig. 6 is a transverse sectional view taken on the line 6—6 of Fig. 5; and Fig. 7 is an enlarged transverse sectional view of a de-

2

tached crane housing and of its supporting track comprised in my invention.

In the embodiment of my invention illustrated in the drawings, a ship of any desired hull type has a weather deck 1 containing hatchways 2, 3 and 4 for ingress to and egress from the fore-hold, mid-hold and aft-hold of the ship.

The edges of the hatchways are bounded by coamings 5 spaced inboard from the gunwales of the ship sufficiently to provide runways 6 extending longitudinally a major portion of the length of the ship's holds and preferably from near the forecastle 7 to near the bridge 8.

Tracks are laid along the runways 6 and preferably each include complementary rails 9 mounted on each coaming 5, complementary rails 10 mounted on a bracket 11 on the deck of each runway 6, and a rail 12 forming a rack lying between the rails 9 and 10 and preferably mounted on a coaming 5.

The complementary rails 9 are vertically spaced from one another to form a race disposed below the coaming channel 13 in which the hatch covers 14 are battened down. The rails 10 are vertically spaced from one another to form a race slightly above the deck of the runway 6.

Carriages 15 are movable along the runways 6; each carriage being provided with flanged wheels 16 engaged in the race formed by the rails 9 and with flanged wheels 17 engaged in the race formed by the rails 10. The rails 9 are adapted to engage both the tops and bottoms of the wheels 16 and the rails 10 are adapted to engage both the tops and bottoms of the wheels 17 so that tilting pressure applied to the carriage in any direction is resisted by the rails 9 and 10, which are designed and mounted to withstand both up and down pressure.

A pinion 18 is mounted on each carriage 15 and meshes with a rack 12. Each pinion 18 may be rotated, to translate its carriage, in any suitable manner, as for instance by an electric motor 19 connected with the pinion 18 through the gearing 20 and shafting 21.

Each carriage comprises a frame having side beams 22 and end beams 23 within which is mounted an annular track 24 having upper and lower edges forming circular rails 25 and 26 cooperating with complementary circular rails 27 and 28 on a cylindrical housing 29 to form raceways for the sets of antifriction rollers 30 and 31; the rollers being held in spaced relation to one another by the cages 32 and 33.

The housing 29 preferably comprises a watertight, ventilated, cylinder having an enlarged annular base 34 to which is attached the rail 28 and an enlarged annular head 35 to which is fixed the rail 27 and on which is formed a rack 36 adapted for engagement by a pinion 37 adapted

to be driven by the motor 38 on the carriage 15 so as to slew the housing around its vertical axis.

The enlarged top 35 of the housing 29 provides a platform 39 on which are journalled the loading drum 40 and topping drum 41, which are driven through suitable gearing and clutches from the electric motors 42 and 43 housed within the housing 29 and shielded thereby from the weather. The drums 40 and 41 have wound thereon the cables 44 and 45 for manipulating the hoist 46 and boom 47 journalled on the bracket 48 on the platform 39. A cab 49 may be mounted on the platform 39 to house the operator and the controllers for the several electric motors.

It will be understood that by manipulating the motor controls from the cab 49, a carriage 15 may be translated along a runway 6 to any desired position lengthwise of the ship, the housing 29 may be slewed about its vertical axis to rotate the boom 47 through any arc requisite to align the boom with any desired spot on a dock, on a lighter, or in the hold of the ship, and the boom 47 and the hoist 46 may be raised or lowered to pick up or deposit a load in any desired spot.

The mountings of the carriage 15 and of the rotary housing 29 on anti-friction supports held against either upward or downward pressure in their respective races obviates the need for counterbalances, and, where a load exceeds in weight the capacity of a single crane, two or more of the cranes may be so positioned as to jointly manipulate such heavy loads.

When the cranes are not in use, the booms may be lowered and lashed fast in the dotted line positions illustrated in Figs. 1 and 2 where they afford no obstruction to visibility or passage under bridges, and even when the booms are in use they present a minimum obstruction to visibility and occasion a minimum of interference with operations within the holds. The cranes may be effectively used in removing, stacking and replacing the hatch covers, and do not interfere with such covers or with the placing of deck loads thereon.

Having described my invention, I claim:

1. A ship having a cargo hold and a weather deck containing a hatchway with a coaming along an edge thereof and a runway adjacent to said coaming, rails extending along said runway and forming a plurality of races, the rails forming one of said races being mounted on said coaming above said deck, a carriage having wheels engaged in said races and held thereby against tilting in either direction, and loading mechanism mounted on said carriage.

2. A ship having a cargo hold and a weather deck containing a hatchway with a coaming along and extending above an edge thereof, a runway adjacent to said coaming, rails extending along said runway and forming a plurality of races and a rack, some of said rails including said rack being mounted on said coaming above said deck, and a carriage having wheels engaged in said races and a pinion meshing with said rack.

3. Ship loading mechanism comprising a frame, a circular track mounted on said frame, a substantially cylindrical housing having radially enlarged upper and lower members complementary to said track and forming therewith a plurality of races, motors within said housing, anti-friction members in said races, and a crane carried by said housing and operable by the motors therein.

4. A ship having a deck containing a hatch-

way with a coaming along an edge thereof, rails mounted on said coaming above said deck and on said deck and forming a pair of races and a rack between said races, a carriage having wheels movable in said races and held by the rails thereof against upward and downward pressure, motive mechanism mounted on said carriage and including a pinion meshing with said rack, a circular track mounted on said carriage, a housing rotatable on said track, propelling means for rotating said housing and including a rack and pinion, drums mounted on said housing, and motor mechanism enclosed in said housing for rotating said drums.

5. A ship having a cargo hold and a deck containing a hatchway and having a runway extending longitudinally along a substantial portion of the length of said hold between said hatchway and the gunwale of the ship, rails extending along said runway and forming a plurality of races and a rack, a carriage having wheels engaged in said races between the rails thereof and held thereby against tilting in either direction, the entire carriage being positioned between an edge of said hatchway and the gunwale of the ship, a weatherproof, cylindrical, hollow rotor rotatable on said carriage about a vertical axis, peripheral rails around said rotor adjacent to the bottom and top thereof, an annular track fixed to said carriage and encircling said rotor between the peripheral rails thereof, rollers between the top and bottom of said annular track and the respective peripheral rails of said rotor, a boom mounted on said rotor and tending, when loaded, to unbalance said rotor and carriage but counteracted by said rails, said wheels and rollers being freely movable relative to the rails engaged thereby notwithstanding the loading of said boom.

6. A ship having a deck with a runway along a gunwale thereof, rails forming spaced raceways extending along said runway, a carriage between said raceways and having wheels engaged between the rails of the respective raceways, said rails holding said wheels against upward or downward movement without substantially impairing their moveability along the raceways, a weatherproof, cylindrical, hollow rotor rotatable about a vertical axis, said rotor being substantially symmetrical in form about said axis, complementary rails on said carriage and rotor for supporting said rotor adjacent to the top and bottom thereof, rollers between the complementary rails last named, said rails and rollers holding said rotor against upward movement, downward movement or tilting movement without substantially impairing the rotatability of the rotor, and a boom fulcrumed on said rotor.
